BOLT LOCK

Harold A. Carlson, University City, Mo., assignor
to Carter Carburetor Corporation, St. Louis,
Mo., a corporation of Delaware

Application January 28, 1946, Serial No. 643,930

1 Claim. (Cl. 151—70)

1

This invention relates to so-called anti-rattler devices, particularly, of the type intended to prevent unauthorized rotation of threadedly attached members with the resultant changing of the relative positions or loosening thereof.

An example of the use of such devices occurs in automotive carburetors in which the idle adjusting screw is carried by the throttle operating arm. The screw engages a stop for limiting the closing movement of the throttle valve and, consequently, the idling position thereof. Since this position is very critical, it is important that the position of the idle adjusting screw in the throttle arm remain fixed after it is properly adjusted. A coiled spring has been symmetrically compressed between the throttle arm and screw head for accomplishing this purpose. However, because of the vibration of the engine and carburetor, this spring has not been wholly satisfactory with the result that the screw, after use for a short time, is frequently found to have rotated and the idling adjustment of the throttle thereby affected.

The main object of the present invention is to provide improved means for resisting unauthorized relative rotation of threaded parts, such as the idle adjusting screw and throttle arm as above described.

A more detailed object is to provide novel means for causing the threads of a screw, such as the throttle adjusting screw, to bind in the holding member.

These objects and other more detailed objects hereafter appearing are attained substantially by the device illustrated in the accompanying drawing in which:

Fig. 1 is a side view of an automotive carburetor with an idle adjusting screw having the invention applied thereto.

Fig. 2 is an enlarged section illustrating a part of the throttle arm and adjusting screw.

Fig. 3 is a view similar to Fig. 2, but illustrating a modification.

The carburetor illustrated in Fig. 1 is of the downdraft type having a choke valve (not shown) in the upper part mounted on a shaft 5 which has an arm 6 rigid with one projecting end thereof. In the lower end of the carburetor there is the usual throttle valve (not shown) mounted on a shaft 7 on one projecting end of which there is rigidly attached throttle operating lever 8. This lever has a hole 9 for attachment of linkage extending to the driver's compartment. A stub shaft 10 adjacent the throttle shaft rotatably mounts a dog or cam 11 which has an apertured arm 12 receiving a link 13 connecting the dog to choke arm 6 for operation therewith.

Idle adjusting screw 15 is threadedly mounted in one portion of throttle arm 8 so as to engage stub shaft 10 or cam 11, according to whether the choke valve is wide open or in its closed position,

15 to limit the closing movement of the throttle valve to the normal or fast idle position. A coiled spring 16 is compressed between the head of screw 15 and the opposing surface of throttle arm 8. As best shown in Fig. 2, this surface of the throttle arm is provided with a non-symmetrical countersink 17 about its threaded opening for screw 15. Thus the portion of the spring which engages the arm is caused to bear against 20 the arm in a resultant direction at an angle to the axis of the screw and, specifically, to the axes of the threadedly attached portions of the screw and throttle arm. The spring thus biases the screw at an angle to cause binding in the threads and, thereby, resist unauthorized rotation thereof.

In the modification shown in Fig. 3, the portion 19 of the adjusting screw 15a immediately adjacent the head thereof is offset or eccentric relative to the axis of the screw. Thus the portion of spring 16 which engages the screw head is similarly off-set so as to bear against the screw head at an angle to the screw axis. As in the previous form, this causes the spring to bias the screw at an angle which results in binding in the screw threads.

Other means may be provided for producing the non-parallel or bias action of the anti-rattler spring. The invention may be modified in various respects as will occur to those skilled in the art and the exclusive use of all modifications as come within the scope of the appended claims is contemplated.

I claim:

35 In a device of the class described, a tapped member, a bolt threadedly received therein, a restricted portion of said tapped member being countersunk about but eccentric to the tapped opening therein, and a coiled spring compressed between said tapped member and the bolt head, 40 said eccentric countersink serving to bias the spring for better resisting turning of the bolt due to vibration.

HAROLD A. CARLSON.
